(57) **CLAIM**

I claim the ornamental design for a protective seal for use in cans or the like for packaging beverages or the like, as shown and described.

DESCRIPTION

FIG. 1 is a first perspective view of a protective seal showing my new design;

FIG. 2 is a second perspective view thereof;

FIG. 3 a front elevation view thereof;

FIG. 4 is a right side elevation view thereof;

FIG. 5 is a rear elevation view thereof;

FIG. 6 is a left side elevation view thereof;

FIG. 7 is a top plan view thereof; and,

FIG. 8 is a bottom plan view thereof.

The broken lines are directed to environment and are for illustrative purposes only. The broken lines form no part of the claimed design.

1 Claim, 3 Drawing Sheets
